CLAIM

The ornamental design for a rounded open core trim piece, as shown and described.

DESCRIPTION

FIG. 1 is a perspective view showing a rounded open core trim piece of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The drawings contain symbolic break lines in FIG. 1 and FIGS. 4–7. The portions of the article between the break lines forms no part of the claimed design.

1 Claim, 6 Drawing Sheets(56)
